UNITED STATES PATENT OFFICE

151,411

DESIGN FOR A MERCHANTISING COUNTER DISPLAY LAMP

Charles S. Rosenberg, Chicago, Ill.

Application May 29, 1947, Serial No. 139,354

Term of patent 14 years

(Cl. D48—20)

To all whom it may concern:

Be it known that I, Charles S. Rosenberg, a citizen of the United States of America and residing in the city of Chicago, State of Illinois, have invented a new, original, and ornamental Design for a Merchandising Counter Display Lamp, of which the following is a specification, reference being had to the accompanying drawing, forming a part thereof.

Fig. 1 is a top plan view of a merchandising counter display lamp showing my new design.

Fig. 2 is an elevational view.

I claim:

The ornamental design for a merchandising counter display lamp, as shown.

CHARLES S. ROSENBERG.
